UNITED STATES PATENT OFFICE.

RICHARD TOENNES, OF BOONVILLE, MISSOURI.

APPARATUS FOR SEPARATING FOREIGN MATERIALS FROM SAND.

1,060,381.

Specification of Letters Patent. Patented Apr. 29, 1913.

Application filed November 9, 1912. Serial No. 730,369.

To all whom it may concern:

Be it known that I, RICHARD TOENNES, a citizen of the United States, residing at Boonville, in the county of Cooper and State 5 of Missouri, have invented certain new and useful Improvements in Apparatus for Separating Foreign Materials from Sand, of which the following is a specification.

This invention is particularly adapted for 10 use on pump-boats whereon are located the engine and other appurtenances for furnishing power to the apparatus and alongside of which is secured the sand-scow to be loaded.

In certain localities, river-sand contains a 15 certain amount of foreign material, such as coal dust and ore of different kinds, and the principal object of this invention is to separate these foreign materials from the sand, to reclaim the ore, especially the gold-ore, 20 but mainly to clean the sand, so that the coal dust or other staining materials will not dis-color the cement work in which the sand is used. This and other objects hereinafter set forth are attained by the means illustrated in the accompanying drawings, in 25 which:—

Figure 1 is an elevation of a pump boat showing my improved apparatus mounted thereon, part being shown in section. Fig. 30 2 is a plan view of the upper portion of the apparatus only. Fig. 3 is a cross-section on the line 3—3, of Fig. 2.

Similar reference numerals in all of the figures of the drawings designate like parts.

35 The apparatus comprises a main trough 4, closed at its rear end as at 5, and provided with a pocket 6 on its underside. In the bottom of the trough 4 adjacent said closed rear end is formed an aperture 7 which communicates with a discharge pipe 8, preferably of a centrifugal suction pump 9, which is provided with the usual suction pipe 10 having a nozzle 11 at its lower end, through which is sucked the sand and gravel from 40 the bottom of the stream.

The upper end of pocket 6 communicates with trough 4 and in the bottom of said pocket is tapped a discharge pipe 12 of a suction pump 13, which is provided with a suction pipe 14 adapted to draw water from 45 adjacent the surface of the stream. In one side wall of the pocket is provided an outlet aperture 15 which communicates with an inclined trough 16 for a purpose hereinafter described, and on a level with the lower side 50 of the aperture 15 and extending across said

pocket, is a screen 17, preferably a perforated plate. A removable cover 18 is provided for an aperture 19 in one of the side walls of said pocket, said cover being provided with a suitable packing to prevent leakage. Covering the top of said pocket 6, is a fine screen 20, preferably formed of longitudinally extending wires only, whereby coarse materials such as gravel, etc., will 60 freely pass thereover. One edge of the screen 17 adjacent the outlet aperture 15 is preferably formed solid to provide a shelf 65 to allow the pure sand to settle thereon and be forced into the sand trough 16.

In the bottom of the trough 4 and between the pocket 6 and the outlet end of said trough, is a discharge opening 21, which communicates with a gravel discharge trough 22, and said opening 21 is also provided with a screen 23 preferably formed like screen 20 but of a coarser mesh to allow gravel to pass therethrough. It will be observed that the upper end of pipe 12 extends above the bottom of pocket 6 thereby forming 70 at the bottom of said pocket and around said pipe a receptacle to receive material heavier than the sand, such as gold ore, etc.

To regulate the pressure of the water in 75 pocket 6 which is discharged therein from the pump 13 and at the same time provide a waste outlet, a pipe 24 is tapped into the side of said pocket below the screen 17 and provided with swiveled section 25 which extends upwardly and forwardly from said pipe. 80 The adjustment of section 25 to and from a vertical position will regulate the pressure of water in said pocket 6. To facilitate the adjustment of section 25, a suitable means is provided thereon for securing said section 85 in its adjusted positions, said means embodying a sliding collar 26 having a set-screw 27 to secure it in position and a lip 28 extending therefrom and adapted to engage the upper edge of trough 4.

In operation, both pumps are started pumping, one delivering sand, gravel, etc., from the bed of the stream to the rear end of the trough 4, and the other delivering water from the top of the stream to the 90 pocket 6. The sand and other material flow toward the discharge end of trough 4, the heavier substances settling on the bottom, and when screen 20 is reached, the sand and fine heavy particles pass through said 95 screen into the pocket 6. The gravel continues on and passes through the screen 23

and discharges into the trough 22, and the lighter materials pass along the trough 4 and are discharged therefrom, usually back into the stream. The sand and fine heavier particles which fall into pocket 6 are thoroughly stirred and agitated by the force of water in said pocket supplied from the pump 13 and according to the pressure regulated by the section 25, the heavy particles such as ore, will drop onto and through the screen 17 into the bottom of the pocket. The sand being lighter than the ore, will be held in suspension above the screen 17 and gradually settle on the solid edge of said screen and pass out into the trough 16. Other foreign material lighter than the sand will be forced upward out of the pocket and carried along with the waste to the discharge end of the trough 4. In this manner clean sand and gravel are separated from the waste material and the ore accumulated to itself.

It will be understood that the several troughs, viz., sand, gravel, and waste troughs, can be extended as desired to deliver to any selected place whether in a boat or upon land.

If desired, the end of the suction pipe 14 can be provided with a nozzle or strainer to prevent debris from entering said pipe.

The force of the water flowing upward through the screen 17 is stronger than when passing through the screen 20 owing to the discharge 15 above the said screen 17, and for this reason, the lighter sand will pass through said discharge 15, the heavier sand and ore will pass through screen 17 and settle on the bottom of the pocket, and the very light materials will pass over the mouth of the pocket without entering, owing to the upward flow of the water from the pocket.

Having thus fully described the invention what is claimed is:

1. In an apparatus of the character described, a trough, means for delivering material to said trough, a pocket in said trough,

a sand discharge from said pocket, a gravel discharge from said trough intermediate said pocket and the outlet of said trough, screens of successively increasing size of apertures over said pocket and gravel discharge respectively, and means for forcing water in said pocket to cause it to flow through said sand discharge and into the trough to separate the lighter from the heavier material in said pocket.

2. In an apparatus of the character described, a trough, means for delivering material to said trough, a pocket in said trough, a sand discharge from the side of said pocket, a screen in said pocket below said sand discharge, a gravel discharge from said trough intermediate said pocket and the outlet of said trough, screens of successively increasing size of apertures over said pocket and gravel discharge respectively, and means for forcing water in said pocket below the screen therein to cause the water to flow through said screen, said sand discharge, and into said trough to separate the lighter from the heavier materials.

3. In an apparatus of the character described, a trough, means for delivering material to said trough, a pocket in said trough, a sand discharge from the side of said pocket, a gravel discharge from said trough intermediate said pocket and the outlet of said trough, screens of successively increasing size of apertures over said pocket and gravel discharge respectively, means for forcing water in said pocket to cause it to flow through said sand discharge and into said trough to separate the lighter from the heavier materials in said pocket, and means communicating with said pocket for regulating the pressure of water therein.

In testimony whereof I affix my signature in presence of two witnesses.

RICHARD TOENNES.
